UNITED STATES PATENT OFFICE.

ESPERANZA DIAZ, OF MEXICO CITY, MEXICO, ASSIGNOR TO EMILIO DE LA PARRA,
JUAN MAS, AND JESUS ANGURES.

TUNING COIL FOR WIRELESS RECEIVING SETS.

Application filed December 18, 1924. Serial No. 756,688.

To all whom it may concern:

Be it known that I, ESPERANZA DIAZ, a citizen of the United States of Mexico, residing at the city of Mexico, Mexico, have 5 invented certain new and useful Improvements in Tuning Coils for Wireless Receiving Sets, of which the following is a specification.

This invention relates to new and useful 10 improvements in tuning coils for wireless receiving sets.

The primary object of this invention is to provide a tuning coil having novel means for varying the inductance of the same.

15 A further object of the invention is to provide novel means for cutting in or out the various turns of an induction winding.

A still further object of the invention is to provide a tuning coil of the above noted 20 type which is of exceedingly simple construction, and one that will maintain its high degree of efficiency for a considerable length of time.

Other objects and advantages of the in- 25 vention will be apparent during the course of the following description.

In the accompanying drawing forming a part of this specification and in which like numerals are employed to designate like 30 parts throughout the same—

Figure 1 is a side elevational view of the tuning coil embodying this invention.

Figure 2 is a horizontal longitudinal sectional view of the device shown in Fig. 1.

35 Figure 3 is a vertical sectional view taken upon line III—III of Fig. 1.

Figure 4 is a diagrammatical view of the tuning coil embodying this invention properly connected in a Reinartz receiving circuit, and

40 Figure 5 is a detail perspective view of a number of turns of the tuning coil winding and indicates the points at which contact is made with the said turns.

45 In the drawing, wherein for the purpose of illustration is shown a preferred embodiment of this invention, the numeral 5 designates a substantially U-shaped frame or support having bearings 6 and 7 formed in the 50 end portions of the same.

The bearing 6 has rotatably mounted therein a sleeve 7 which rotatably supports within its bore a tubular shaft 8 having a shaft 9 rotatably received within its bore. The end 10 of the shaft 9 is journaled in 55 the bearing 7 of the frame or support 5.

Suitably secured to the shaft 9, between the arms of the U-shaped frame or support 5 are a plurality of cross arms 11 which connect the cylinder 12 to the said shaft. 60 This cylinder 12 has a plurality of integrally formed, circumferentially extending flanges 13 formed thereon and between which are wound the turns of the primary and secondary windings 14 and 15 of the 65 tuning coil. The primary winding 14 is provided with the leads —a— and —b— while the secondary winding 15 is provided with the leads —c— and —d— which extend thru suitable openings formed in 70 the cylinder 12 for projecting into the bore of the said cylinder.

The cylinder 12 has formed integrally therewith or suitably secured thereto the spirally extending rib 16 which underlies 75 the turns of the secondary winding 15, in the manner illustrated in Figs. 3 and 5, for raising the overlying portions of the said turns, which overlying portions are to be scraped for exposing the conducting portions 17 of 80 the insulated wire forming the winding.

The cylinder 12 is further provided with a pair of spirally extending ribs 18 and 19 which underlie the turns of the primary windings 14 and function in the same manner as the rib 16 underlying the secondary winding 15, it being understood that the turns of the primary winding 14 are to be scraped to expose the conducting portions 90 of the wire forming this winding in the same manner as shown in Fig. 5 in connection with the secondary winding.

The arm of the U-shaped frame or support 5 which has the bearing 7 formed therein is provided with a stationary contact arm 20 which is insulated from the frame or support by the bushing 21. This stationary contact arm 20 is preferably formed of round stock and is positioned to engage the uninsulated or exposed portions 100

17 of the secondary winding 15 for variably connecting the said turns of the winding with the lead-off wire 22 attached to the supported end of this arm 20. A resilient member 23 is provided for maintaining the arm 20 in contact with the turns of the winding 15, it being understood that this resilient member 23 may be insulated from the arm 20 or the frame or support 5 in any suitable manner for preventing the same from electrically connecting the members 5 and 20. The cylinder 12 is to be rotated by means of the knob 24, secured to the shaft 9, for causing relative movement between the exposed portions of the secondary winding 15 and the stationary contact arm 20 for cutting in or out the number of turns of the said windings. Movement of the cylinder 12 is limited by the stops 25 which engage 20 the arm 20.

The tubular shaft 8 has a knob 26 attached thereto at the end adjacent the knob 24 and has a laterally projecting arm 27 secured to its remaining end. This arm 27 has connected to its free end a movable contact arm 28 which is insulated by the bushing 29 and is connected to the lead-off wire 30. This movable contact arm 28 is intended to be adjusted in respect to the exposed or uninsulated portions of the primary winding 14 which overlie the spiral rib 18. The resilient member 31, similar to the member 23, is employed for maintaining the movable contact arm 28 in engagement with the winding 14. 35 This arm 28 is to be moved in respect to the winding 14 by the knob 26 and is to be limited in its movement in respect to the winding 14 by the stops 32, carried by the cylinder 12.

40 The sleeve 7' has mounted on one end thereof the knob 33 by means of which the sleeve may be rotated. The remaining end of this sleeve has connected thereto the arm 34 which carries the movable contact arm 35 at its outer end. This contact arm 35 is insulated from the arm 34 by the bushing 36 and is connected to the lead-off wire 37, as shown. A resilient member 38, similar to the member 23, is employed for maintaining 45 the movable contact arm 35 in engagement with the exposed or uninsulated portions of the primary winding 14 which overlie the rib 19. The contact arm 35 is limited in its movement in respect to the winding 14 by 50 the stops 39 which are carried by the cylinder 12.

60 It will now be seen that by rotating the knob 25, the entire cylinder 12 with the windings 14 and 15 will be rotated in respect to the frame or support 5. This rotation of the cylinder 12 will cause the spirally arranged exposed portions of the secondary winding 15 to move relative to the stationary contact arm 20 for causing the arm 20 to 65 contact or be connected to different turns of

this winding, thereby varying the inductance of the secondary coil. By operating the knobs 26 and 33, the movable contact arm 28 and 35 respectively may be shifted in respect to the turns of the primary winding 14 for 70 varying the inductance of the same.

In Fig. 4 there is shown a diagrammatical view of a Reinartz circuit with the tuning coil embodying this invention properly connected therein. It is not believed necessary 75 to specifically describe the circuit illustrated or the manner of connecting the various tuning coil terminals thereto for this tuning coil is not limited in its use to this particular type of winding nor the particular manner 80 of connecting the coils to the type of circuit illustrated.

It is now believed that the method of constructing and the manner of operating this tuning coil will be understood from the 85 above detail description. It is further to be understood that the form of this invention herewith shown and described is to be taken as a preferred example of the same, and that various changes in the shape, size, 90 and arrangement of parts may be resorted to without departing from the spirit of the invention or the scope of the subjoined claims.

Having thus described the invention, I 95 claim:

1. In a tuning coil of the type described, a support, a cylinder, means for rotatably mounting the cylinder on said support, a pair of windings on said cylinder, each 100 winding having a spirally extending line of uninsulated places, means for raising the uninsulated places above the remainder of said windings, a stationary contact arm carried by said support and traversing one winding in engagement with its line of uninsulated places, a contact arm carried by said support and traversing the other winding in engagement with its line of uninsulated places, said last mentioned contact arm being concentrically movable around said cylinder, means 105 for rotating said cylinder to cause the stationary contact arm to engage successive uninsulated places in its associated winding, and means for moving the second mentioned 110 contact arm for causing it to engage successive uninsulated places in its associated winding.

2. In a tuning coil of the type described, a support, a cylinder, means for rotatably mounting the cylinder on said support, a pair of windings on said cylinder, each winding having a spirally extending line of uninsulated places, ribs for raising the uninsulated places above the remainder of said windings, a stationary contact arm carried by said support and traversing one winding in engagement with its line of uninsulated places, a contact arm carried by said support and traversing the other winding in en- 115 120 125 130 135 140 145 150 155 160 165 170 175 180

gagement with its line of uninsulated places, contact arm for causing it to engage successive uninsulated places in its associated winding.
said last mentioned contact arm being con-
centrically movable around said cylinder, a
knob for rotating said cylinder to cause the
5 stationary contact arm to engage successive
uninsulated places in its associated winding,
and a knob for moving the second mentioned

In testimony whereof I hereunto affix my
signature.

10

ESPERANZA DIAZ.
